UNITED STATES PATENT OFFICE.

ALEXANDER NULLAU, OF BERLIN-NIEDERSCHONHAUSEN, GERMANY, ASSIGNOR TO BERGMANN-ELEKTRICITÄTS-WERKE, AKTIENGESELLSCHAFT, OF BERLIN, GERMANY, A CORPORATION.

LOOM.

Application filed February 18, 1926, Serial No. 89,173, and in Germany May 28, 1925.

This invention relates to looms. It more particularly relates to a shuttle actuating device for the loom.

Ordinarily the reciprocating movement of the shuttles in mechanical looms is effected by means of impact devices actuated through eccentrics or cranks from the loom itself. These impact devices, while operating very simply and surely, are defective in that their force of impact are dependent upon the speed of the loom. It is impossible to acquire, with a low rate of rotation, the necessary force of impact, consequently it is impossible when such impact devices are used 10 to run the loom slowly or to stop it except by employing special means for sharply accelerating and suddenly stopping the looms.

It is old in the art to provide impact devices which are dependent upon the speed of 20 operation of the loom. Also it has been suggested that the impact devices be actuated by means of a spring. In such an arrangement the impact is then given with uniform force independently of the speed and the operation 25 will thus be carried on at any desired low speed of the loom. Impact devices so constructed however, are impractical because their inertia is too great for use with a high speed loom drive as commercially desired.

An object of this invention is to provide 30 means for a loom whereby it will be possible to utilize such shuttle actuating devices as crank or eccentric impact members, which operate independently on the speed of operation of the loom, while at the same time, the shuttle movement may be made independent within certain limits of such speed, thus enabling the loom to properly operate efficiently at very low speeds.

Other objects and advantages will herein-after appear.

The invention contemplates providing the shuttle actuating device intended for normal speed with a further shuttle actuating device adapted to be actuated when the normal speed is deviated from. This may be accomplished by providing an impact device dependent on the rate of rotation of a rotating member of the loom during high speed 45 use of the loom and another impact device independent of the rate of rotation thereof.

for use during low speed operation of the loom.

A specific manner in which the above will be accomplished is shown in the accompanying drawing and described in the following specification.

The drawing shows diagrammatically in Figure 1 the position of the impact device when the loom is started and operating below a predetermined upper limit of low speed; Figure 2 illustrates the position assumed by the said device when the loom is in operation at speeds above said upper limit of low speed operation and Fig. 3 is a fragmentary detail to an enlarged scale of the starting and latch control mechanism.

A drive shaft 1, for the impact device, mounted in suitable bearings on the supporting framework F, has fixed thereto the tappet 2 and cam disk 3. An impact lever 4 is pivoted at its lower end to the framework F, and, intermediate its ends, carries a roller 5 mounted rotatably on the lug 5' to engage the edge of cam disk 3, a spring 6 secured at 70 its opposite ends to the framework F and lever 4 serving to hold said lever 4 with its roller 5 in yielding contact against cam disk 3.

A roller 7 rotatably mounted on stub shaft 7' extends perpendicularly from the shaft 7" rotatably mounted on framework F, and is held normally in the path of rotation of the tappet 2 by means of the coil spring S having one end thereof fixed to the framework F and the other fixed to shaft 7". The stops S' and S", fixed to shaft 7" and framework F respectively serve to limit the rotation of the shaft 7" to position the roller 7 properly for wiping contact by tappet 2, 80 or for throw by the pusher arm 8 extending from the oscillatory lever 4. A picker or impact arm 9 is fixed to the upper end of shaft 7".

The arm 8 is of such length, and the tappet 2 and disk 3 are so positioned on shaft 1 that when the roller 5 snaps off the widest part of cam disk 3 the curved end 8' of arm 8 engages roller 7 so far ahead of tappet 2 as to push the roller 7 out of the path of tappet 2 and permit the latter to pass without wiping rollers 7. It will therefore, be

obvious from Figure 1 of the drawing, that unless some means be provided for holding arm 8 with its end 8' clear of roller 7 the throw of the picker 9 will be wholly controlled by the spring 6, and that regardless of the speed of rotation of shaft 1 (speed of operation of the loom), the shutter-throw impact of picker 9 will be constant.

At high speeds of operation, the spring 10 throw of the picker may be too sluggish, and it becomes necessary to provide means for operating the picker at speeds which vary directly as the speed of operation of the loom. In order to secure this, the starting mechanism of the loom is constructed so that up to a predetermined upper limit of low speed operation, the throw of picker 9 is controlled wholly by the spring 6. Above this limit, the lever 4 with roller 5 20 is locked out of operative contact with cam disk 3, and the throw of picker 9 is effected wholly by wiping contact of tappet 2 with roller 7.

The control panel 10 has one end of the 25 control lever 11 pivoted thereto to swing over the control contacts 12, and the other end of lever 11 is slidably pivoted to the end of a slotted latchrod 13 which slides in a guide bracket 14 fixed to framework F.

30 A latch lever pivoted intermediate the ends on pin 16 fixed to frame work F, has one arm 17 thereof slidably in a slot 18 of rod 13 and has its other and heavier arm 19 provided with a lug 20 adapted to hook over a projection 21 formed on lever 4. When the loom is stopped the upper end 18' of slot 18 slidably engages the upper edge of lever arm 17 to hold the lever tilted with the lug 20 out of engagement with 35 projection 21. When the loom is started by swinging the lever 11 upwardly over contacts 12, the latchrod 13 is pulled up vertically. The weighter arm 19 keeps the upper edge of arm 17 in contact with end 40 18' of slot 18, and the lug 20 lowers toward the path of projection 21. As the lever 11 is further raised to its limit, the lower end 18'' of slot 18 engages the lower edge of arm 17 and holds the latch lever with its 45 lug 20 locked with projection 21. The outer edge of lug 20 is cam shaped so as to permit the projection 21 to slide into locking engagement with lug 20 when the latch lever is positioned for engagement therewith, and 50 a stop 22 on framework F prevents the weighted arm of the latch lever from swinging it beyond the position where it is adapted to snap over projection 21.

It will be obvious that the slot 18 is provided so as to afford a lost motion connection between the loom starting mechanism and the lever latching means; and it will also be obvious from Fig. 2 that when the lever 4 is latched, the throw of picker arm 55 9 is controlled wholly by wiping contact of

tappet 2 with roller 7, and that the speed of operation thereof is in direct proportion to the speed of rotation of shaft 1 and therefore of the loom itself.

In operation: When the loom is started 70 the latch rod 13 is pulled upwardly and the latch lever lowers with the upper edge of its arm 17 in contact with end 18' of slot 18 until its said edge contacts with stop 22, when it will be in position to engage and lock lever 4 as the latter oscillates to the left. The arm 8 is then held from contact with roller 7, and the tappet 2 operates the picker 9 in direct proportion to the speed of the loom. The slot 18 is provided to 80 permit further increase in the speed of the loom beyond the speed at which lever 4 is oscillated, and the lower end 18'' of slot 18 merely engages the lower end of arm lever 17 when the loom is operating at top speed. 85

In stopping the loom, as the lever 11 is 90 swung downwardly, the speed of the loom decreases, but the lever 4 remains locked until the end 18' engages lever arm 17; after which engagement, further lowering of lever 11 raises lug 20 out of locking engagement with projection 21, and the picker arm 9 is then brought under control of spring 6 and remains under such control 95 until the loom is stopped.

The lever 4 must be retained in the check position when the loom is driven in the opposite direction. The reason for this is apparent because the engagement of the roller 5 against the cam disc would prevent such 100 reverse movement. The shifting of the lever 4 in the checked position would take place in the other direction of rotation dependently on the reversal of the drive motor by means of a system of rods used for this purpose. It 105 is understood, of course, that the loom should have two such impact devices in order to provide for the reciprocal movement of the shuttle. The invention thus enables the loom to be driven at a lower speed than would normally be possible. In other words, the loom may be started slowly and stopped slowly. The result is that the mechanical strain ordinarily exerted on the loom and on the material being treated thereby, are eliminated because there is no necessity of rapid starting and sudden stopping. It is apparent that operative disturbances heretofore taking place will be lessened and that it will be possible to utilize a smaller driving 110 motor. It should also be observed that the simple means above described for accomplishing these advantages may be readily installed on looms now in operation. 115

It is hereby expressly stated and understood that the invention is susceptible of many modifications and adaptations within the scope of the appended claims. 125

What I claim is:

1. In a loom, a shuttle actuating device, 130

- means for operating said device with constant force at all speeds below a predetermined speed of operation of the loom, and mechanism for preventing the operation of said means when the speed of the loom exceeds said predetermined speed. 5
2. The combination with the apparatus set forth in claim 1, of means for operating said shuttle device while the first named means is prevented from operation by said mechanism. 10
3. In a loom; a shuttle actuating device; spring controlled means for operating said device; means independent of said spring controlled means for operating said device; and mechanism to prevent the effective operation of either of said means during the operation of the other. 15
4. In a loom; a shuttle actuating device; means operable with constant force for operating said device; means independent of the first named means for operating said device; and mechanism to prevent simultaneous effective operation of said means. 20
5. In a loom; a support; a shuttle actuating device pivoted on said support; a member pivoted on said support; mechanism for oscillating said member to operate said device; means independent of said member for operating said device, said member preventing effective operation of said means while the member is in operation; and means to prevent operation of said member when the speed of the loom exceeds a predetermined limit. 30
6. In a loom; a shuttle actuating device; means capable of operating said device with constant force at all speeds of the loom; and mechanism for holding said means inoperative when the speed of the loom exceeds a predetermined limit and when the loom is reversed. 35
7. In a loom, a support, a shaft rotatably mounted thereon; a picker fixed to said shaft; means for holding said shaft yielding in a predetermined angular position, an arm extending perpendicularly from said shaft, spring controlled member engageable with said arm to oscillate said shaft, a tappet rotatable to have intermittent impinge contact with said arm; means for rotating said tappet; and mechanism to prevent simultaneous engagement of said member and tappet with said arm. 40
